CLAIM

The ornamental design for a hood mask, as shown and described herein.

DESCRIPTION

FIG. 1 is a left front perspective view of a hood mask showing my new design in a closed state configuration;

FIG. 2 is a front elevational view thereof;

FIG. 3 is a rear elevational view thereof;

FIG. 4 is a left-side elevational view thereof;

FIG. 5 is a top plan view thereof;

FIG. 6 is a bottom plan view thereof; and

FIG. 7 is a left-side cross-sectional view thereof taken along lines 7-7 of FIG. 2.

FIG. 8 is a left front perspective view of the hood mask as shown in an open state configuration;

FIG. 9 is a front elevational view thereof;

FIG. 10 is a rear elevational view thereof;

FIG. 11 is a left-side elevational view thereof;

FIG. 12 is a top plan view thereof;

FIG. 13 is a bottom plan view thereof; and,

FIG. 14 is a left-side cross-sectional view thereof taken along lines 14-14 of FIG. 9.

The jacket outlined by broken lines assists to illustrate the environment of the hood mask and forms no part of the claimed design. The person outlined by broken lines in FIGS. 1 and 8 assists to portray the hood mask in a position of use and forms no part of the claimed design.
